Term of patent 14 years

Int. Cl. D23—146

U.S. Cl. D23—146

FIG. 1 is a perspective top view of a combined air scoop and duct coupling collar assembly for a humidifier unit, showing my new design;

FIG. 2 is a perspective bottom view thereof; and

FIG. 3 is a side elevation view of the same, the opposite side being substantially the mirror image thereof.

I claim:

The ornamental design for a combined air scoop and duct coupling collar assembly for a humidifier unit, as shown and described.
